CONCENTRATOR FOR MINERALS IN FINE
SIZED RANGESThomas S. Bailey, Jr., Denver, Colo., assignor to
Mining Process and Patent Company, Denver,
Colo., a corporation of Delaware

Application May 5, 1947, Serial No. 746,050

4 Claims. (Cl. 209—490)

1

This invention relates to concentration of minerals and more particularly relates to apparatus for the concentration of fine-sized heavy minerals.

In many ore milling operations valuable minerals occur in such small percentage of the ore content that it is not economically feasible to recover such content by the usual ore dressing methods, such as froth flotation or table concentration, for example. Despite the economic complications, it frequently is desirable to recover such minerals due to their scarcity, as in the case of tin, or for other reasons.

It is an object of the present invention to provide simple, durable and efficient apparatus for the concentration of low-grade ores and particularly adapted for the concentration of minerals in size ranges of from 150 to 1000 mesh.

Another object of this invention is to provide simple, economical and efficient apparatus for concentrating low-grade ores which is capable of handling a relatively large tonnage with little wear on the operating parts utilized in the treatment.

A further object of the invention is to provide simple, durable, and efficient apparatus which provides a relatively high ratio to concentration in the treatment of low-grade minerals.

The present invention resides in the discovery that rigidized or relatively stiff metal sheets, if properly corrugated and arranged to be alternately tilted to opposed inclined positions will effectively trap a heavy mineral of an ore pulp flowing across the corrugated surface in the series of recesses formed therein, and such mineral may be washed from the metal surface during tilting in the opposite direction so as to separate such mineral from other constituents of the ore.

The practice of the present invention will be best understood by reference to the accompanying drawings. In the drawings, in the several views of which like parts have been designated similarly,

Fig. 1 is a side elevation of concentrator apparatus embodying features of the present invention;

Fig. 2 is a fragmentary plan view of a portion of one of the decks shown in Fig. 1, taken in the approximate position of the line 2—2, Fig. 1;

Fig. 3 is a fragmentary section taken approximately along the line 3—3, Fig. 2 across the table and direction of pulp flow; and

Fig. 4 is a fragmentary plan view, drawn to an enlarged scale, of the deck shown in Fig. 2.

As shown in Fig. 1, the concentrator C com-

2

prises a frame 5, on which a series of superposed decks 6 are mounted on pivot pins 7 for movement to oppositely inclined positions, as indicated by the full line and dotted line representations. Tilting of the decks from one said position to the other is effected through the intermediary of a suitable motor M, speed reducer R, and transmission T, here shown as a chain and sprocket drive.

10 An ore pulp requiring concentration is fed through a feed distributor 8 by which it is selectively delivered onto one end of the respective decks 6 of the unit. Due to the inclination of these decks, the pulp flows from one end to the 15 other of each deck during a predetermined period. In this action, the recesses 9 (Fig. 4) trap the heavy mineral tending to settle in the flow across the decks. The gangue discharging across the ends of the decks passes through a spout 10 to 20 waste. As illustrated, the recesses have curved bottom portions and are substantially diamond shaped with the major axis transverse to the direction of flow of material on the deck and with the minor axis parallel to said flow. Each side 25 of the recess is defined by a ridge and the several recesses are in staggered relation so as to cause a zig-zag travel of material along the surface of the deck, in which travel a substantial lateral spreading is imparted to the material passing across the ridge dividing one recessed area from another.

Thereafter, the decks are tilted by the aforesaid mechanism to the dotted line positions shown in Fig. 1, while at the same time a wash 35 liquid, such as water is delivered through header 12 and supply pipes 13, each provided with a series of apertures 14 so as to wash the decks 6 for removal of the entrapped mineral, which ultimately flows across the ends of said decks and 40 eventually flows out of spout 15, where it is collected or delivered to suitable treatment apparatus.

In order to demonstrate the effectiveness of the concentrating method just described, a series 45 of comparative tests were undertaken, in which the same treatment was performed on the same material, except that the deck surface was changed for each series of tests.

In each case a 1000 gram charge of ore was 50 pulped to 20% solids and passed over the concentrator in 5 minutes. In one series of tests the decks were covered with rubber matting of conventional design. In the next series of tests, the decks were covered with rigidized metal of the type shown in Fig. 4. From the results ob-

tained and from observations made during the tests, it is believed that the corrugated metal surface is superior to conventional rubber decks for the following reasons:

1. A higher grade of concentrate was produced because the rubber surface tends to hold the gangue as well as the metallic sulphide.

2. A higher recovery was made because the rubber became saturated with gangue, and the desired metallic sulphide was allowed to escape.

3. Mechanical manipulation in washing the concentrate from the table was much faster and easier with the metal covering than with the rubber units.

4. Termination of the washing period may be positively determined with the metal surface whereas it was always questionable with the rubber surface.

The results of this comparative testing follow:

Test A

Product	Percent Weight	Percent Pb	Percent Recovery Pb
Calculated Heads.....	100.00	0.67	100.00
Concentrate.....	2.90	17.64	76.67
Tailings.....	97.10	.15	23.33

CHECK TEST

Calculated Heads.....	100.00	0.71	100.00
Concentrate.....	3.2	18.03	80.98
Tailings.....	96.8	.14	19.02

REMARKS.—Two 1000 gram charges of minus 100 mesh heads were passed over the Denver-Buckman tilting concentrator using the metal decking and the above results were obtained. Direction of pulp flow was at right angles to the long dimension of the indentations on the metal plate.

Test B

Product	Percent Weight	Percent Pb	Percent Recovery Pb
Calculated Heads.....	100.00	0.72	100.00
Concentrate.....	4.1	12.45	70.76
Tailings.....	95.9	.22	29.24

CHECK TEST

Calculated Heads.....	100.00	0.65	100.00
Concentrate.....	3.8	11.07	64.56
Tailings.....	96.2	.24	35.44

REMARKS.—Two 1000 gram charges of minus 100 mesh heads were passed over the Denver-Buckman tilting concentrator using the standard rubber decking and the above results were obtained.

From the foregoing test operations, it will be apparent that there is a distinct advantage in the use of the metallic surfaces in the concentrator. However, for some purposes it may be desirable to employ more of a friction surface and this may be done by spraying the metal with a suitable rubber compound, by painting, or by applying an adhesive in which lint, hair or other materials may be embedded.

In the preferred arrangement, valve means are provided to control the flow from header 12 into each of the distributors or supply pipes 13. When the ends of the decks carrying the supply pipes are in the down position, the valves remain closed and the pulp fed onto the deck at its opposite end flows down the deck by gravity. In this action, the heavier constituents, regardless of size, descend through the body of material and are trapped in the elongated recesses, while the lighter constituents discharge into spout 16.

After a given amount of feed has thus descended along the deck, the motor M and speed reducer R operate to tilt the deck in the opposite

direction and at the same time the valves (not shown) open to allow a flow into the supply pipes 13 and through openings 14 onto the decks. This flow washes the mineral concentrate out of the recesses and off the ends of the decks into the receptacle 15.

At the end of the concentrate discharge interval, the control mechanism again tilts the decks to the alternate position, the wash liquid supply 10 cuts off, and a new charge of feed is delivered onto the decks. In this way, the succession of actions serves to effectively separate the valuable constituents from the gangue and is particularly effective when the valuable constituents are present in size ranges finer than -150 mesh.

The present invention may be utilized in the concentration of a variety of materials, as for example, wolframite, cassiterite, gold, scheelite, oxides, and tarnished materials. Typical applications 20 of the use of the concentrator are low grade placer deposits, retreating tailings dumps, and increasing the efficiency of the slime section in gravity plants.

While the apparatus illustrated in the drawings represents a preferred structural arrangement, it will be understood that the deck surfaces may be arranged in a variety of ways to effect the separation of heavy and lighter materials. Therefore, the description of such structural arrangement is not intended to limit the invention, but to explain the practice of the invention, the scope of which is defined in the hereunto appended claims.

What I claim and desire to secure by Letters 35 Patent is:

1. In an ore concentrator, a material receiving deck formed of a substantially stiff metal sheet, the upper surface of which has a series of shallow, substantially diamond-shaped recesses arranged in staggered sequence lengthwise of the deck with their major axes transverse to the flow of material along the deck and their minor axes parallel to said flow, each said recess being defined by a curved bottom portion sloping 40 to ridges on each of its sides, each of which ridges separates one recess from two adjoining recesses of the series, said deck being mounted for movement to oppositely inclined positions about a pivotal support, means for directing a wash liquid onto the elevated end of the deck in one position, and mechanism for tilting the deck.

2. In an ore concentrator, a material receiving deck formed of substantially stiff metal sheet, the upper surface of which has a series of shallow, 45 substantially diamond-shaped recesses arranged in staggered sequence lengthwise of the deck with their major axes transverse to the flow of the material along the deck and their minor axes parallel to said flow, each said recess being defined by a curved bottom portion sloping upwardly to ridges on each of its sides, each of which ridges separates one recess from two adjoining recesses of the series, trunnion means for pivotally supporting the deck for tilting movement about a horizontal axis, means for directing a wash liquid onto one end of the deck, and means for tilting the table about the trunnion means.

3. In an ore concentrator, a material receiving deck formed of a substantially stiff metal sheet, the upper surface of which has a series of shallow, substantially diamond-shaped recesses arranged in staggered sequence lengthwise of the deck with their major axes transverse to the flow 50 of material along the deck and their minor axes

parallel to said flow, each said recess being defined by a curved bottom portion sloping upwardly to ridges on each of its sides, each of which ridges separates one recess from two adjoining recesses of the series, a thin coating of organic material having a high coefficient of friction on the metal surface, trunnion means for pivotally supporting the deck for tilting movement about a horizontal axis, means for directing a wash liquid onto one end of the table, and means for tilting the table about the trunnion means.

4. In an ore concentrator, a material receiving deck formed of a substantially stiff metal sheet, the upper surface of which has a series of shallow, substantially diamond-shaped recesses arranged in staggered sequence lengthwise of the deck with their major axes transverse to the flow of material along the deck and their minor axes parallel to said flow, each said recess being defined by a curved bottom portion sloping upwardly to ridges on each of its sides, each of which ridges separates one recess from two adjoining recesses of the series, said deck having pivotally supported near its mid-point for tilting movement about a horizontal axis to oppositely inclined positions, means for directing a

wash liquid onto one end of the deck, and means for tilting the deck about said horizontal axis.
